W. E. PETTINGILL

JORDAN ENGINE

Filed March 8, 1923

Fig. 2.

Walter Edwin Pettingill, Inventor:

Dodge and Sons,
Worcestor

UNITED STATES PATENT OFFICE.

WALTER EDWIN PETTINGILL, OF EAST PROVIDENCE, RHODE ISLAND, ASSIGNEE TO
BIRD & SON, INC., OF EAST WALPOLE, MASSACHUSETTS, A CORPORATION OF MASSA-
CHUSETTS.

JORDAN ENGINE.

Application filed March 8, 1923. Serial No. 623,733.

To all whom it may concern:

Be it known that I, WALTER EDWIN PETTINGILL, a citizen of the United States, residing at East Providence, in the county ⁵ of Providence and State of Rhode Island, have invented certain new and useful Improvements in Jordan Engines, of which the following is a specification.

My present invention pertains to Jordan ¹⁰ engines which, as is well known to those skilled in the art, are commonly employed for refining paper, rag or other stock prior to the passage of the stock to the screens.

Heretofore, so far as I am aware, the ¹⁵ material to be treated has been fed to the engine at the smaller or head end thereof, the feed opening being arranged radially and directly adjacent such small or head end. Under this arrangement the stock ²⁰ feeds endwise under pressure of the head of the stock in between the knives or blades on the plug and the shell. As a consequence, as the blades wear down and the plug is moved in endwise to compensate for such ²⁵ wear, the size of the openings between the blades becomes smaller and the degree of feed is proportionally reduced. With a view of increasing the feed capacity I heretofore moved the feed opening longitudinally ³⁰ of the shell at some distance from the head end of the machine but still retaining or maintaining the radial arrangement of the intake pipe or feed channel. Such arrangement was found in actual practice to be defective as it was impossible to get the ³⁵ stock into the jordan. The stock seemed to plug up in the opening. The thick stock apparently acted as a filter, gradually reducing the flow of water owing to an accumulation of fine stuff by the coarser until finally all inflow of water and stock ceased.

After the failure of such arrangement I conceived of the present invention which broadly stated, consists in arranging the ⁴⁵ feed opening or pipe at a tangent to the circumference of the plug, whereby unlooked for increase in capacity, with a marked conservation in power, was obtained. Furthermore, under the new arrangement, a longer time interval between necessary replacement of the bars or knives likewise obtains.

A Jordan engine embodying my inven-

tion is illustrated in the annexed drawings, ⁵⁵ wherein,—

Fig. 1 is a side elevation of the improved engine; and

Fig. 2 a transverse vertical sectional view on the line II—II of Fig. 1, with parts broken away. ⁶⁰

In said figures, 1 denotes the shell or casting of standard outline, except for the feed inlet, said shell being provided with the usual removable heads 2 and 3, in which latter is provided the discharge 4. Said ⁶⁵ outlet may be adjusted about the head 3 to effect the discharge from the engine at the desired level.

The cone or plug 5 is of standard form having spaced bars or blades 6 extending ⁷⁰ longitudinally thereof. The cone is secured to a shaft 7 mounted in suitable bearings so constructed as to admit of longitudinal adjustment of the cone or plug within the shell to compensate for wearing down of ⁷⁵ the bars. The shell liner is denoted by 8, and the bars or knives carried thereby by 9. The feed inlet or delivery channel, which may be round, square, or, in fact, any desired shape, is denoted by 10, and the liner ⁸⁰ is cut away beneath the inner end thereof, the liner bars or knives also being omitted at such point or space. As will be seen the inlet is arranged tangentially of the cone and shell and by preference the inlet, instead ⁸⁵ of opening into the neck of the shell as is usually the case, it is placed further along on the shell.

This arrangement of the feed affords an increased size of opening by introducing ⁹⁰ the stock upon an arc to one side of the highest point or top of the cone so that the material is fed to and rests upon that portion of the cone which throughout the extent of the opening is travelling downward and away from the opening. Thus, the momentum of the stock is in no wise retarded, as it is when the opening is arranged radially or at right angles, but is caught by the knives on the downgoing side ⁹⁵ 100 of the revolving cone and dragged down into the machine.

The gradually narrowing opening or the substantially V or wedge shaped feed channel as it may be termed, with the rotating ¹⁰⁵ cone face with its bars forming the bottom

of such channel, serves to feed the stock into the machine at a rapid rate. As a consequence the material passes through the jordan at an increased speed. This method of introducing the stock has been found to double the capacity of a jordan. Where heretofore with the usual equipment I have been able to handle less than 40 tons in 24 hours, I am able with the same equipment 10 modified so as to introduce the material tangentially to handle over 80 tons in the same time interval with a material saving in power.

Moreover, repairs are much less per ton of 15 stock used. One reason for this is that I am enabled to use the plug longer than I could with the old feed entrance, and this without materially reducing the capacity of the machine. The wearing down of the knives or 20 bars does not seriously affect the capacity so long as there is any "bucket" left between the knives.

Again the jordan, with my invention applied thereto, will take and handle a relative 25 rough and half-beaten stock; as a consequence it is not as necessary to reduce the stock in the beaters so far as under the old conditions.

The machine produces a free working 30 stock, but refines the same sufficiently for handling in the usual screens and in the remainder of the process to which the screened stock is subjected.

What is claimed is:

35 1. In a Jordan engine, the combination of a shell; a plug mounted for rotation therein;

a series of bars or knives carried by each of said members; and means for introducing stock directly on the bars of the plug on the down-going side thereof and likewise 40 against the adjacent portion of the shell and the bars carried thereby.

2. In a Jordan engine, the combination of a shell having bars or knives arranged interiorly thereof; a plug mounted for rotation 45 therein; bars or knives arranged exteriorly thereof; and a feed inlet for the stock to be treated arranged tangentially of the plug, the inlet opening directly onto the knives of the cone and the co-acting adjacent face of 50 the shell.

3. In a Jordan engine, the combination of a shell having bars or knives arranged interiorly thereof; a plug mounted for rotation 55 therein; bars or knives arranged exteriorly thereof; and a wedge shaped inlet for the stock formed between the wall of the shell and the down-going side of the plug.

4. In a Jordan engine, the combination of a shell having a neck portion; a feed opening arranged tangentially thereof and at a point removed from the neck, said opening discharging directly onto the adjacent wall 60 of the shell; knives located interiorly of the shell except at that portion where the feed opening is located; a plug mounted for rotation in the shell; and knives carried by the plug.

In testimony whereof I have signed my name to this specification.

WALTER EDWIN PETTINGILL.
